United States Patent

Des. 239,043
Patented Mar. 2, 1976

239,043

DOLL

Pamala A. Lander, 4060 Andeson Circle,
Sacramento, Calif. 95826

Filed May 30, 1973, Ser. No. 365,068

Term of patent 14 years

Int. Cl. D21—01

U.S. Cl. D34—4 C

FIG. 2.

FIG. 1.

FIG. 4.

FIG. 3.

FIG. 1 is a front elevation view of a doll embodying my new design;

FIG. 2 is a side elevation view of the same;

FIG. 3 is a rear elevation view of the same; and,

FIG. 4 is an enlarged view taken along lines 4—4 in FIG. 2 showing details thereof.

The characteristic feature of my design resides in the particular form of the eyes in combination with the doll configuration shown.

I claim:

The ornamental design for a doll, substantially as shown and described.
